UNITED STATES PATENT OFFICE.

JAMES F. DORAN, OF DANBURY, CONNECTICUT.

APPARATUS FOR SOFTENING HATS.

Application filed December 26, 1919. Serial No. 347,406.

This invention relates to softening hats. One of the objects thereof is to provide a simple and efficient means for supplying fluid for softening hats. Other objects are 5 a means of the above nature which will avoid impurities, which will prevent dampening of the hat, and which shall furnish a jet of the desired form and size. Another object is to provide an art of hat-softening 10 which shall be practical and readily carried on and present various features of advantage. Other objects will be in part obvious and in part pointed out hereinafter.

The invention accordingly consists in the 15 features of construction, combinations of elements, arrangement of parts and in the several steps and relation between such steps, all as will be hereinafter illustratively set forth and the scope of the application of 20 which will be indicated in the following claims.

In the accompanying drawings in which is shown one of various possible embodiments of the mechanical features of this 25 invention,

Figure 1 is a side elevation with the applying device and its attachments broken away;

Figure 2 is a top plan view of the parts 30 shown in Figure 1;

Figure 3 is a vertical section taken on the line 3-3 of Figure 2; and

Figure 4 is a detail side elevation partially in section showing an applying device 35 and its mounting.

Similar reference characters refer to similar parts throughout the several views of the drawing.

Referring now to these drawings in detail, there is diagrammatically indicated in Figure 1 at 10 a source of fluid supply adapted to furnish fluid under pressure. From this source of supply the fluid, which may be air although for most of the features of this invention steam may be employed, is led through the valve 11 of the ordinary globe type. The valve however, is provided at its lower end with an extremely small drip opening 12 for a purpose herein after described.

Adjacent valve 11 is a piece of apparatus comprising a supporting portion 13 having legs 14 secured as by the screws 15. This support 13 forms the lower portion of a casting 16 and has a number of walls or

flanges 17 of the form indicated in Figure 2 of the drawings. These walls are such as to lead the fluid which enters as hereinafter described, at 18 through a circuitous passage indicated by the arrows. This passage first 60 comprises the outer portion 18 through which the fluid circulates about the apparatus to the port 19, from which it passes into the next inner passage 20 making a reverse turn through the port. In circulating 65 through the passage 20 it makes another reverse turn at the port 21 circulating in the reverse direction to the port 22, at which it again reverses and traverses the passage 23 until it reaches the outlet port 24 positioned above the inner end of the passage 23, as shown in Figure 3 of the drawings.

These various passages formed by the flanges or walls 17 are closed at the top by a hollow casting 25 which is bolted upon 75 the top of the casting 16. This hollow casting is preferably filled with mineral wool as at 26 in order to avoid undesirable radiation of heat, and is covered by a cap 25a held in place by a bolt 25b.

The apparatus immediately above described is provided with a gas heater 27 which may be fed by a suitable pipe 28 and which serves to apply intense heat to the underside of the casting 16.

Taking up now the matter of the connections between the valve 11 and the apparatus immediately above described, reference is made to Figure 1 in which is shown an elbow 29 connected by a suitable piping with 90 the valve 11. This elbow is provided with a downward extension 30 leading to a drip cock 31, but its main outlet is to a pipe 32 connected as by the nipple 33 with a chamber formed in the lower portion 13 of the 95 casting 16. This chamber, shown at 34 in Figure 1, is provided with a pair of screens or straining devices 35 and 36. The screen 35 is held upwardly across the outlet port from chamber 34 by means of a collar 37 and 100 the screen 36 is held downwardly against the inner end of the nipple at 38 by means of a collar 39, the collars 37 and 39 being resiliently urged apart by the spring 40. This entire device is readily removable by un- 105 screwing the nipple 33, and may be cleansed or renewed and quickly re-assembled. It tends to screen out all impurities, and also, particles of moisture which collect on the underside of the screens drip downwardly.

110

and may be removed through the drip cock 31. It may also be noted at this point that if the drip cock 31 be left closed and any moisture accumulate at any part of the apparatus while it is not in use, it slowly drips off at the opening 12, thus precluding the chance of an accumulation of water which might be converted into steam at unduly high pressure.

From the chamber 34 the fluid passes through port 34^a into the labyrinthine passage formed by the walls 17 as above described in which it is subjected to intense heat from the burner 27, the flames of which are enclosed by the lower extension 13 of the casting 16.

From the labyrinth which is so formed as to drain the segregated moisture out through the fluid inlet opening 34^a, the dried and purified fluid is led through port 24 and a passage 41 cored out in the upper casting 25. From 41 an elbow 42 conducts the fluid to a valve 43 by which the discharge is controlled. On valve 43 is mounted an applying device which is shown only in Figure 4 of the drawings. This applying device comprises a casting 44 to which is secured as by screw 45 a bracket 46. The outer end of this casting has an opening preferably of oval form, but the fluid in passing through such opening is forced to traverse a sheet of asbestos cloth 47 and a superposed piece of wire screening 48, both held in position as by means of the wire 49, clamping them into a groove 50.

Hinged to the bracket 46 at pin 46^a are a series of plates, here two in number, 51 and 52. The innermost of these plates is provided with an opening 53 of the oval or other desired form and substantially smaller than the opening which would be provided if the plates were both removed. The outer plate is provided with an opening 54 of an even smaller area. The supporting pin 55 supports one or both of these plates swung backwardly out of operative position, or this may also be done by a shoulder 56 on the plates if desired. In this manner three different sizes of effective openings are afforded according as both plates are swung back, the inner plate is swung forward into action, or both plates are swung forward. The number of plates could obviously be increased at will.

Considering now the method of use of the apparatus above described, the fluid under pressure passes through the valve 11 and particles of moisture and impurities removed by means of the screens or strainers 36 and 35. It then passes into the labyrinthine passage and due to the conformation of this passage, it is further dried by centrifugal action, the moisture being drained away through the inlet passage 34^a. During this stage, furthermore, the fluid is

intensely heated and if steam should be employed, it is given many degrees of superheat. On leaving this passage, its discharge may be controlled by the valve 43 and applied by the device shown particularly in Figure 4 of the drawings. This device is of such size and shape as to localize the highly heated and dried air, or in some cases steam, to the precise portion of the hat which it is desired to soften. Furthermore, it is given a final purification by the asbestos cloth and screen through which it is discharged. In softening hats it is desired to apply heat without undue moisture, the heated fluid alone performing the softening function. Furthermore, the area which it is desired to affect is subject to wide variation. Hence the plates 51 and 52 are so manipulated as to afford an opening of substantially the desired size. Over this opening the hat is held and the jet of heated fluid so directed as to produce the most efficient softening effect.

Although as hereinbefore noted, steam may be employed, there are certain advantages inherent in air, due to the greater degree of dryness which it may be given, and other factors.

It is to be noted that full drainage for the entire apparatus is provided, the applying device being vertically arranged and all parts leading thereto being free from depressions in which water may gather and leading backwardly to the drip cock 31. It is also to be noted that the several purifying devices 35, 36 and 47 are readily removed as for cleansing and renewal. By this careful cleansing action, minute particles of dirt and other foreign matter are removed, whereas otherwise they would be driven into the softening hat and necessitate cleansing of the latter, or in some cases permanently injure or discolor it.

It will thus be seen that there is provided apparatus in which the several mechanical objects of this invention are achieved and that there is herein set forth an art in which other objects are attained.

As various possible embodiments of the mechanical features of this invention might be made and as various changes might be made in that embodiment herein set forth, and as the art herein described might be varied, all without departing from the scope of my invention, it is to be understood that all matter herein set forth or shown in the accompanying drawings is to be interpreted as illustrative and not in a limiting sense.

I claim as my invention:—

1. In hat softening apparatus, in combination, a device having a passage for fluid therethrough, means adapted to heat said fluid flowing through said passage, and a device connected to said passage for applying said heated fluid to a hat including

an outlet opening against which the hat is adapted to be placed and means for varying the cross section of said opening.

2. In hat softening apparatus, in combination, a device having a passage for fluid therethrough, means for heating said fluid flowing through said passage, and a device connected to said passage for applying said heated fluid to a hat, including an outlet opening having a fibrous member stretched thereover and means exterior thereof for varying the cross sectional area of the stream passing therefrom.

3. In hat softening apparatus, in combination, a device having a passage for fluid therethrough, means for heating said fluid flowing through said passage, and a device for applying said heated fluid to a hat connected to said passage and including a plurality of superposed plates having successively smaller openings before which the hat is adapted to be held. 15
20

In testimony whereof, I have signed my name to this specification this 11th day of December, 1919.

JAMES F. DORAN.
